(57) **CLAIM**

The ornamental design for a handle for flatware, as shown and described.

DESCRIPTION

FIG. 1 is a front elevational view of my new design for a handle for flatware shown on a knife;

FIG. 2 is a left side elevational view thereof;

FIG. 3 is a right side elevational view thereof;

FIG. 4 is a rear elevational view thereof;

FIG. 5 is a bottom plan view thereof;

FIG. 6 is a cross-sectional view taken along lines 6—6 of FIG. 1 thereof;

FIG. 7 is a cross-sectional view taken along lines 7—7 of FIG. 1 thereof;

FIG. 8 is a front elevational view of my new design for a handle for flatware shown on a fork;

FIG. 9 is a left side elevational view thereof;

FIG. 10 is a right side elevational view thereof;

FIG. 11 is a rear view thereof;

FIG. 12 is a bottom plan view thereof;

FIG. 13 is a cross-sectional view taken along lines 13—13 of FIG. 8 thereof;

FIG. 14 is a cross-sectional view taken along lines 14—14 of FIG. 8 thereof;

FIG. 15 is a front elevational view of my new design for a handle for flatware shown on a spoon;

FIG. 16 is a left side elevational view thereof;

FIG. 17 is a right side elevational view thereof;

FIG. 18 is a rear view thereof;

FIG. 19 is a bottom plan view thereof;

FIG. 20 is a cross-sectional view taken along lines 20—20 of FIG. 15; and,

FIG. 21 is a cross-sectional view taken along lines 21—21 of FIG. 15.
